[57] CLAIM

The ornamental design for a knife blade, as shown and described.

DESCRIPTION

FIG. 1 is a side elevational view, a handle therefor being shown in phantom, of a knife blade showing my new design;

FIG. 2 is a top plan view thereof;

FIG. 3 is a side elevational view of the side opposite from that shown in FIG. 1;

FIG. 4 is a rear end view thereof; and,

FIG. 5 is a front end view thereof.

The handle shown in phantom is for illustrative purposes and forms no part of the invention.
